UNITED STATES PATENT OFFICE.

JAMES H. TAYLOR, OF PAWTUCKET, RHODE ISLAND, ASSIGNOR OF ONE-HALF TO
THOMAS RILEY, OF PAWTUCKET, RHODE ISLAND.

MACHINE FOR FORMING CALKS.

1,184,893.

Specification of Letters Patent.

Patented May 30, 1916.

Application filed January 16, 1914. Serial No. 812,407.

To all whom it may concern:

Be it known that I, JAMES H. TAYLOR, a citizen of the United States, residing at Pawtucket, in the county of Providence and State of Rhode Island, have invented certain new and useful Improvements in Machines for Forming Calks, of which the following is a specification.

My invention relates to a machine for automatically forming, from a metal blank, calks adapted for use in horse shoes. It has heretofore been attempted to make calks by drop forging, which method has been slow and expensive. It has been considered impossible to employ rolls for this purpose because of the problem of disposing of the surplus metal that is necessarily displaced by the compression of the rolls and which naturally advances before the rolls in the direction of the movement of the rolls and thus would either distort the metal pattern or prevent the operation of the rolls.

The essential objects of my invention are to form calks automatically by rolling rather than by forging; and to attain this end by a mechanism or devices, easy to operate, inexpensive to construct, and which shall produce a maximum of calks in a minimum of time.

To the above ends primarily my invention consists in such parts and in such combination of parts as fall within the scope of the appended claim.

In the accompanying drawings which form a part of this specification, and wherein like reference characters indicate like parts throughout the views: Figures 1 and 2 are front and side elevations respectively of my machine, Fig. 3, a section on *u u* of Fig. 1, Figs. 4, 5 and 6, side, front, and plan views respectively of the feeding device. Fig. 7, a section of the same on line *v v* of Fig. 4. Fig. 8, a section of the dies and adjacent parts on line *w w* of Fig. 1. Figs. 9 and 10, flat developments of portions of the top and bottom die peripheries respectively, Fig. 11, an enlarged partial section of the dies on line *x x* of Fig. 8, Fig. 12, a complete section on line *x x* of Fig. 8, Figs. 13 and 14, sections on lines *y y* and *z z* respectively of Fig. 10, Figs. 15 and 16, front and side elevations respectively of a finished calk, Fig. 17 an enlarged section of a modified form of my invention taken on a line corresponding to line *x x* of Fig. 8, Figs. 18 and 19, flat developments of portions of modified top

and bottom die peripheries respectively, and Figs. 20 and 21, end and side elevations of the roll pin.

In the embodiment of the present invention the assemblage of parts may comprise, in a general way, a base 2, and shaft housings 3 and 4, which housings are identical in construction, and a description of one will serve for both, similar reference numerals being employed for corresponding parts, each housing in the present instance comprising vertical guide ways 5 in which are located, with a sliding fit, split bearing blocks 6, for the driving shaft 7. Resting upon these is block 8 provided with a central vertical bore 9, in which is a helical spring 10 whose lower end presses against the block 6, and whose upper end presses against a split bearing block 11, which rests upon the block 8 and supports a driven shaft 13. This spring forms a yielding cushion between the blocks 6 and 11. Upon the tops of the vertical guide ways 5 of the housings 3 and 4 are respectively retaining plates or straps 15 and 16 removably attached by bolts 17 and 18 or otherwise. One end of the driving shaft is mounted in an auxiliary bearing 20 upon the end of the bed, and has fixed thereto a wheel 22 driven by a belt 23 from any source of power. Adjacent to this driving wheel upon the shaft is a balance wheel 24. Intermediate the housings upon the driving shaft are driving gears 26 and 27 meshing respectively with gears 28 and 29 fixed to shaft 13. The teeth of gears 28 and 29 are preferably timed, one slightly in advance of the other, in order to compensate for backlash.

In order to meet the great strain which might otherwise tend to spring the shafts 7 and 13, an auxiliary bearing frame is provided, best shown in Fig. 2. This comprises a yoke or cross piece 32 provided with a central bearing or bore 33 for the shaft 13, and which is slidable on vertical posts or rods, 35, fixed at their lower ends to a cross piece 36, provided with a central bore 38 in which is journaled the end of the shaft 7. The piece 32 is retained against excessive vertical movement by nuts 39 upon the upper ends of the rods, and which bear against the upper face of the cross piece. On intermediate portions of the rods 35 are shoulders 40 supporting helical springs 41, surrounding the posts and bearing against the under face of the piece 32.

Fixed to shafts 13 and 7 respectively are two rolls 43 and 44. The member 43 comprises a core 45 and provided with an annular recess 46 at one end to receive a shoulder 47 of the shaft. It has also a peripheral annular shoulder 49 at one end. Seated upon the periphery of the core is an annular die 50 which abuts against the shoulder 49 and projects beyond the same. Screws 51 are located at intervals in openings 52 in the die and engage in threaded openings 54 in the shoulder. Resting against the side of the core and die is a retaining plate 56 held in place by a washer 57 and nut 58, the latter engaging threads 60 on the shaft. Roll 44 is identical in construction, comprising the core 61, flange 62, die 63, screws 64, and retaining plate 65. A nut 67 and washer 68 engage respectively the threads 69 on shaft 7, and the shaft itself. The form of cores and dies herein disclosed adapts the same for a ready change of dies, but it is evident that such is not absolutely essential.

The face of the die 50 is provided with a series of depressions and elevations or cutting edges shown in detail in Figs. 9 and 11. Two spaced parallel annular shoulders 70 and 71 upon the ends of the die periphery form partitions for the stock to be operated upon. Extending transversely of the die half its width from the shoulder 71 are a series of spaced substantially semi-circular depressions 73. Alternating with the depressions 73 are inclined depressions 75 of the same length as the depressions 73 but of greater breadth. The depressions 73 and 75 are separated by parallel transverse shoulders or cutting edges 78. The other half of the die face has alternating transverse depressions 79 and 80, similar to 73 and 75 in shape and dimensions, but in staggered relation to each other. The depressions 79 and 80 are separated by parallel shoulders 84. The inner ends of the shoulders 84 may be connected with the inner ends of shoulders 78 by shoulders 85 in alignment with each other. The depressions 73 and 79 are deeper than the depressions 75 and 80.

The die 63 is similar in general construction to the die 50. It has the partition shoulders 87 and 88. Adjacent the latter are alternate depressions 89 and 90 corresponding in form and arrangement with depressions 73 and 75. Depressions 94 and 95 similar in shape and location to 79 and 80 are adjacent the partition 87. Parallel shoulders 98 separate the depressions 89 and 90; shoulders 99 separate depressions 94 and 95; shoulders 100 connect the ends of shoulders 98 and 99. The locations of shoulders 98, 99 and 100 correspond with those of shoulders 78, 84 and 85 of the companion die 50. The depressions 89 and 94 are generally deeper than the depressions 95 and 90.

It will be observed that the transverse disposition of the walls or edges 78, 84, and 98, 99 upon the die peripheries, tends to prevent the accumulation of metal in advance of the contacting point of the dies, which accumulation would choke or stop the advance of the dies and prevent any rolling operation. The transverse disposition of the companion cavities also assists in disposing of the otherwise surplus metal. The general depths of the portions 73, 79, 89 and 94 being greater relatively to the general depths of their corresponding adjacent transverse portions 80, 75, 95 and 90 respectively, causes the greater masses of metal in the former portions to move or be squeezed transversely into the latter portions, thus still further preventing the accumulation of a choking mass, and disposing of surplus metal.

As the metal blank passes between the rolls 43 and 44 each die shapes one half of each unit formed by the coöperation of the die faces, it being understood that the shoulders 78, 84, and 85 are timed to contact or nearly contact with the shoulders 98, 99, and 100, whereby the material between these shoulders is either severed or rendered so thin as to make it possible to divide the resultant units into the constituent parts manually. By reference to Figs. 15 and 16 the form of the resultant unit may be observed in the finished calk consisting of a tapering head 102 and a cylindrical shank 104. The heads are formed by the depressions 75, 80, 90, and 95, while the shanks 104 are formed by the depressions 73, 79, 89, and 94.

If preferred each die may be split on the line of shoulders 85 and 100, thus making two companion die members on each roll. The advantages of this in practical use are convenience in grinding the die faces, and lessening the expense of any accidental breakage of the die surface. In Figs. 17, 18 and 19 is shown this modified form of my invention.

The upper die 50 is herein shown as two adjacent dies 109, 110; and the lower die 63, as independent annular dies 111 and 112. In actual use the absence of the central annularly arranged series of shoulders 85 and 100 from the modified die couplets or from the original dies does not interfere with, nor are they essential to, the perfection and efficiency of the product of the rolls. These split dies may be mounted, like the integral dies, on their respective rolls in any convenient manner. In the present instance the dies 109 and 110 have abutting against their respective outer faces bearing rings 115 provided with perforations 116. The plate 56 has also perforations 117. Through these two sets of perforations and the openings 52 of the dies pass the bind-

ing screws 51. The split dies 111 and 112 are similarly mounted on rolls, having bearing rings 120 held against the dies by the screws 64.

5 The blank is guided and controlled by the following device. A bracket or supporting plate 122 is fixed by screws 123 or otherwise to the end of the machine base 2, and has intermediate its length an arm or extension 125 provided with an inclined upper face carrying a guide plate 127 provided with a base 128 adjacent the dies and provided with marginal flanges 129. The guide plate is in the present instance attached to the extension 125 by an adjusting screw 130 passing through an oblong slot 131 in the extension 125 and engaging a threaded opening 132 in the guide plate. A screw 133 in plate 122 may also engage a threaded opening 134 in member 127. In the forward portions of the flanges 129 is a pin 135 on which is mounted a guide roller 136. The blank, when fed by hand, is passed over the guide plate 127 in contact with the roller 136. In feeding blanks of smaller breadth an auxiliary guide 138 is placed between the flanges 129. This plate comprises a base 139 and side flanges 139', and rests partially on plate 127 and partly on 30 a spacing block 140 on the said plate. A screw 142, passing through the block engages in a threaded opening 143 in the base 139 of the auxiliary guide.

In order to uniformly and intermittently feed the blank over the auxiliary guide the following device is employed. A supporting bar or plate 145 rests on the extension 125 and is fixed intermediate the plate 122 and plate 127 by the screw 133 passing 40 through an opening 146 in said bar. A longitudinally slidable bar 148 rests on this plate beneath a rib 149 on the plate 122. On the forward end of the slide 148 is a rounded shoulder 150, and spaced therefrom a stop 45 projection 151. The shoulder 150 is in the path of a pin 153 provided with a base 154 adjustably fixed in a radial way 154' shown in Figs. 20 and 21 on the side of the roll 43 whereby the slide is forwardly reciprocated at each revolution of the rolls. The 50 change of the radial position of the pin varies the degree of advance of the blank.

In the rear portion of the slide 148 is a longitudinal slot 155 through which extends a pin 156 on which are washers 158 at each side of the slide. Upon the threaded end portion of the pin is a nut 160 bearing against one washer; also a butterfly nut 161 abutting against the other washer. A block 60 163, pivoted upon the outer end of the pin, registers between the flanges 131 of the auxiliary guide plate and is adapted to engage the rear end of the blank in the guide.

The slide is rearwardly tensioned by a spring 165 having one end attached to hook 166 65 on the bottom of the slide, and its other end engaging a pin 167 fixed in an extension plate 168 fixed to the plate 127 by a screw 170 passing through a longitudinal slot 171 in the extension plate. This screw 70 and slot arrangement permits adjustment of the tension of the spring. The block 163 advances a blank at each advance of the slide 148, and for blanks of different lengths the radial position of the pin 153 is changed. 75 For convenience a lug 173 on plate 122 is perforated to serve as a holder for a pin 174 which may be used, when desired, to lock the slide relatively to the rest of the mechanism, by inserting it in openings 176 80 and 177 in the slide and in the plate 122 respectively.

Upon the rear side of the housing 3 is an integral extension 178 having a pin 179 which passes through an eye 180 in a plate 85 181 fixed to the bottom of a guide plate 182 whereby the latter is pivoted intermediate its length as shown in Figs. 2 and 4. The forward end of this plate is retained near the periphery of the lower die by 90 virtue of a spring 184 having its lower end attached to the plate 181 in the rear of the pivot pin 179, and its upper end attached to a pin 185 in an arm 186 integral with the extension 178. The plate 182 prevents 95 the stock from adhering to the lower die, and has marginal flanges 188 to guide the material. Its forward end is supported by a rod 189 in the housing 3. To guide the material from the upper die a curved arm 100 190 contacts with the die, and is supported by a roller 191 on a pin 192 in the extension 178. The arm is pivoted on a pin 194 in said extension.

What I claim is:—

In a machine for forming calks, the combination of coöperating rolls, each roll being provided with a series of transversely disposed alternating curved and noncurved depressions, and with a second series of similar transversely disposed depressions parallel with the first series and with the respective depressions in staggered relation with respect to the depressions of the first series, transverse partitions upon each roll 110 bounding the several depressions and adapted to register with the partitions upon the other roll, when the rolls are rotated, and means for rotating the rolls in unison 115 with each other.

In testimony whereof I have affixed my signature in presence of two witnesses.

JAMES H. TAYLOR.
